DESIGN FOR A SHOE OR THE LIKE

George Codish, New York, N. Y., assignor to Craft Sole Sales Company, Paterson, N. J., a partnership composed of George Codish, Jonas A. Senter, and Max Potash

Application January 5, 1945, Serial No. 117,280

Term of patent 14 years

(Cl. D7—7)

To all whom it may concern:

Be it known that I, George Codish, a citizen of the United States, residing in New York city, county of Bronx, State of New York, have invented a new, original, and ornamental Design for a Shoe or the like, of which the following is a specification, reference being had to the accompanying drawing, forming a part thereof.

Figs. 1 and 2 are perspective views of a shoe showing my new design.

I claim:

The ornamental design for a shoe or the like, as shown.

GEORGE CODISH.
